AKTIENGESELLSCHAFT, OF BERLIN, GERMANY, A CORPORATION OF GERMANY.

ELECTRIC SIGNALING APPARATUS.

1,150,054.

Specification of Letters Patent. Patented Aug. 17, 1915.

Application filed June 28, 1912. Serial No. 706,370.

To all whom it may concern:

Be it known that I, ERNST GEORG MISSBACH, a subject of the German Emperor, and residing in the borough of Manhattan, city, 5 county, and State of New York, have invented certain new and useful Improvements in Electric Signaling Apparatus, of which the following is a full and clear specification illustrated in the accompanying 10 drawing, and the particular novel features being more fully pointed out in the annexed claims.

This invention relates to an electrical signaling system which is operated by alternating currents whereby by means of equalizing currents the angular position of the sending apparatus is caused to be transmitted upon the receiving apparatus.

More particularly the present invention 20 relates to a system of this kind, whereby a plurality of signals, for instance, numbers containing two or more digits, or generally combination signals whose elements or units are in a fixed interdependence from each 25 other, such as angular degrees, minutes and seconds, or the like, may be transmitted from a sending to a receiving apparatus. In this case it has so far been customary to employ electrical connections between each sending 30 element, and its corresponding receiving element. In my co-pending application, Serial Number 706,368 filed of even date herewith, I have described a system of electric signaling, whereby auxiliary mechanical means 35 are employed in addition to the regular electrical connections between the corresponding sending and receiving elements. In my present system for the sake of simplicity, I propose to use electrical connections only 40 between one sending element and its corresponding receiving element, and to employ a mechanical gearing means between the several elements of the receiving as well as of the sending station. My present invention, 45 therefore, considerably reduces the amount of electrical apparatus which heretofore has been customary with signaling systems of this kind.

My invention will be more fully understood by reference to the accompanying diagrammatic drawing of which,

Figure 1 represents an elevation of the sending apparatus; Fig. 2 is a plan view thereof, Fig. 3 an elevation, and Fig. 4 a 55 plan view of the receiving apparatus.

Referring now more particularly to the drawing, 10 represents the unit dial bearing the ciphers from zero to nine in equal distribution upon its circumference, said dial being mounted upon the shaft 11 together with 60 the armature 12 only shown in Fig. 2 diagrammatically as so-called three-phase alternating current "delta" connection. Upon the same shaft 11 there is mounted a disk 13 which carries a pin 14 at a certain point of 65 its circumference. This pin 14 cooperates with a toothed wheel 15, mounted upon the shaft 16 of the second element of the sending station. This second element, likewise, is equipped with a dial 17 similar to the dial 10 of the first element. Upon the shafts 16 and 11 are mounted notched disks 19 and 20 respectively, which are retained in a plurality of angular positions by the levers 21 and 22 respectively. These levers are pivot- 70 ed at their upper end and spring pressed as shown at 23 and 24 respectively, and bear a roller at their lower end, said rollers engag- 75 ing the notches of the wheels 19 and 20, all as clearly represented in the drawing. In 80 this manner the dials 10 and 17 are retained in their proper positions to present the digits contained upon their circumference in alignment to each other and with the opening 25. 85

The receiving apparatus is identical to the sending apparatus, except in that the handle 26, which is used for manually operating the sending device, and the retaining device for the receiving armature are omitted. The 90 corresponding devices of the receiving apparatus are denominated by the same figures as given above for the device of the sending apparatus, by addition of the index "a." 10^a is the dial for the units of the receiving 95 apparatus mounted with disk 13^a on shaft 11^a. The disk carries the pin 14^a, which meshes with the toothed wheel 15^a mounted upon the shaft 16^a. This shaft also carries the disk 17^a which carries the "tens" digits 100 at its periphery. Corresponding with Figs. 1 and 2 19^a, 21^a and 23^a are the elements comprising the retaining mechanism for the "tens" disk 17^a. The armature 28 which operates shaft 11^a is indicated only in Fig. 105 4 diagrammatically and similar to Fig. 2 by showing a three phase alternating armature in "delta" connection. The broken off portions of shafts 11 and 11^a indicate that these armatures are supposed to be mounted on 110

the portions of their respective shafts not shown.

The electrical connections for the present system of electric signaling are as follows:

- 5 The armature 12 of the sending apparatus having a three-phase alternating current winding is connected by means known in the art, such as slip-rings and brushes (not shown here) and conductors 27 with the
- 10 corresponding elements of armature 28^a of the receiving apparatus having a similar winding. The fields in which the armatures rotate are represented diagrammatically by coils 28 at the sending station and coils 29
- 15 at the receiving station. The field coils 28 and 29 are connected to a single phase alternating current source 30 by means of the conductors 31 and 32. It is well known in the art that if in such an arrangement of
- 20 armatures and fields one armature is moved angularly (as for instance by turning handle 26 in Fig. 2), currents are set up in the armature circuits, which tend to turn the other armature (in this case 28^a) an equal
- 25 angle, when such currents cease to flow.

The operation of my present apparatus is therefore as follows: In order to transmit a desired combination signal, for instance the number 90 having two digits, from the sending to the receiving apparatus, the operator has to move the unit element at the sending station by means of the handle 26 until the desired two-digit number appears underneath the opening 25. The tens dial will follow the unit-dial in such an order that upon one full revolution of the latter, the former will rotate one tenth of its circumference. In other words, upon passage of the zero of the unit-dial into the opening 40 25 the tens-dial will move one step forward and present the succeeding numeral underneath said opening. The motion of the ten element at the sending station is not directly transmitted to the ten element of the receiving station by electrical means. On the

other hand, the dial for the tens at the receiving station, in a mechanical way, properly follows the unit-element in entirely the same manner as the ten-element will follow the unit element at the sending station. 50

Having thus described my invention, I do not wish to confine myself to the precise constructions as shown and described herein, since modifications may be made thereon without departing from the principle or sacrificing any of the advantages of this invention, but

I claim as new and desire to secure by Letters Patent of the United States:

1. An electric signaling system of the character described, having a sending apparatus comprising a plurality of elements, capable of definite relative motion to represent a signal, a receiving apparatus comprising a like plurality of elements, electrical connections between one of said sender elements, and the corresponding receiver element, a mechanical gearing means between the several elements of the sending apparatus and between the several elements of the receiving apparatus, whereby combination signals may be transmitted by said electrical connections between only one of the sender elements and one of the receiver elements. 65

2. An electric signaling system for combination signals having a sending apparatus comprising an element for smaller units, and an element for larger units which is mechanically coupled with the former element, a receiving apparatus having similar elements which are correspondingly arranged, and electrical connections between the sender and receiver elements denominating the smaller units. 70 75 80

ERNST GEORG MISSBACH.
